US0D1032202S

(12) **United States Design Patent** (10) **Patent No.:** **US D1,032,202 S**
(45) **Date of Patent:** **** Jun. 25, 2024**

(54) **DISPLAY STORAGE BOX**

(71) Applicant: **Carmelo Phillip Giaimo**, City Beach
(AU)
(72) Inventor: **Carmelo Phillip Giaimo**, City Beach
(AU)

(**) Term: **15 Years**

(21) Appl. No.: **29/777,417**

(22) Filed: **Apr. 6, 2021**

(51) LOC (14) Cl. **03-01**
(52) U.S. Cl.
USPC **D3/294; D7/610**

(57) **CLAIM**

The ornamental design for a display storage box, as shown and described.

DESCRIPTION

FIG. 1 is a perspective view of a display storage box, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing of bottom features is for the purpose of illustrating portions of the display storage box that form no part of the claimed design.

1 Claim, 7 Drawing Sheets
